UNITED STATES PATENT OFFICE

2,676,508

STUD FOR EXPLOSIVE INSTALLATION

Virginius R. Erickson, Portland, Oreg., assignor
to Powder Power Tool Corporation, Portland,
Oreg., a corporation of Oregon

Application October 18, 1952, Serial No. 315,598

6 Claims. (Cl. 85—10)

1

The present invention relates to stud driving tools of the type employed for installing studs by explosive action in wall surfaces, such as concrete and steel, and is concerned more particularly with the provision of an improved stud embodying means for maintaining its position in the bore of the barrel of a tool.

In accordance with the instant invention, the stud is provided with a frictional portion or element or improved character to hold the stud in place in the tool, which enables easy entry of the stud into the breech end of the barrel, which is not lost easily from the stud in handling of the studs before use, which is not apt to be blown off during the explosion, and which does not require care in packaging and is adapted to packaging in a box.

The above and other objects of the invention are attained in certain preferred embodiments of the invention as described in connection with the accompanying drawings, in which:

Figure 1 is an elevational view of a stud driving tool employing the invention, with a portion of the tool adjacent the combustion chamber broken away and shown in section to illustrate details of construction.

Figure 2 is a side elevational view of a stud as shown in Figure 1.

Figure 3 is an end elevational view of the stud shown in Figure 2.

Figure 4 is a fragmentary enlarged cross-sectional view of the stud as installed in the bore of the barrel, the view being taken as indicated by the line 4—4 in Figure 1.

Figures 5 and 6 are elevational views of a modified form of stud.

Figure 7 is a side elevational view of another modified stud.

Referring to Figure 1, there is shown a stud driving tool of the character described and claimed in the co-pending application of Daniel T. Phillips et al., Serial No. 274,172, filed February 29, 1952, for Stud Driving Tool. In general, stud driving tools of this character are adapted to be separated or broken into two halves including a rear half 10 which contains the various fire control parts, including, for example, a firing pin carrier 11, and a front or barrel half 12 of the tool in which the barrel 13 is included. The barrel 13 is provided with a threaded rear end 13a which has a threaded connection within the end of the firing pin carrier 11 to connect the two halves of the tool. The barrel 13 is also provided with an enlarged bore to receive a removable breech plug 14 in which the explosive cartridge

2

15 is mounted for impact by the firing pin of the firing mechanism. With the parts disassembled, the breech plug 14 is removed and the selected stud 17 is installed in the barrel, the cartridge 15 is placed in the breech plug 14, and the parts are reassembled as shown in Figure 1 for a firing operation. Firing is accomplished by placing the end of the barrel 13 against the surface into which the stud is to be driven and pressing or 10 telescoping the barrel assembly 12 and the firing pin carrier 11 back into the other portions of the tool until a firing position is reached, as disclosed in said application, and then effecting relative turning movement of the central housing 15 and the end grip 18 to fire the tool. At this time 15 the deflector pad structure 19, yieldably mounted about the barrel 13, is engaged with the surface about the area of engagement of the end of the barrel so as to provide protection from flying 20 particles of the wall surface upon explosive installation of the stud.

Referring in particular to Figures 1, 2, 3 and 4, the stud 17 is of special construction and includes a frictional portion or element which is 25 used to frictionally hold or secure the stud in a selected adjusted position in the barrel against movement in either direction. Studs of this general type are disclosed and claimed in the co-pending application of Webber and Erickson, Serial No. 136,186 filed December 31, 1949, and granted as U. S. Letters Patent No. 2,637,241, on May 5, 1953, for Stud for Explosive Installation. The improved stud shown herein includes the usual sharpened point 17a and the head 17b 35 which is of a diameter to fit closely but freely within the bore of the barrel 13. The stud 17 also includes a shank 17c intermediate the point and the head which may include a straight, knurled portion 17d. The stud carries the frictional element 21 which is in the form of a plastic sleeve or tube having a circular array of radially extending fins 22. The fins 22, as seen in Figures 3 and 4, are of slightly greater diameter than the head 17a of the stud and are deformed or flexed laterally when inserted in the bore of the barrel. The frictional retainer 21, by virtue of the engagement of its fins 22, within the bore of the barrel, aids in maintaining the stud properly centered with respect thereto, and 40 by virtue of this fact enables a reduced length, when desirable, of the head 17b of the body of the stud. The side walls of a fin 22 are preferably parallel to facilitate flexing thereof. The retainer portion of the stud also facilitates packing the studs in boxes and tends to maintain a 45 50 55

stable position thereof during shipment and handling. The frictional retainer portion of the stud may be constructed of any suitable flexible, resilient material, such as paper, plastic, rubber, or the like, to be readily removable or destructible, but is preferably of a vinyl resin which is readily combustible or friable so that the ring will be destroyed or substantially destroyed by burning during the expelling of the stud from the tool.

In the modification shown in Figures 5 and 6, a stud 17 is shown including a frictional retainer element 23 whose radially extending fins 24 have a generally triangular cross-section.

Referring to Figure 7, in this form of the invention the stud 17 includes a frictional retainer 26 whose parallel fins 27 which are generally similar to those shown in Figures 2 and 3 but which are twisted or of spiral configuration to provide a "rifling" effect for the stud during its travel along the barrel. This effect increases the stability of the stud after it leaves the barrel of the tool while penetrating the work surface.

The frictional retainer shown can be made as an extruded plastisol tubing which is cut to the desired length.

While I have shown and described certain preferred embodiments of the invention, it will be apparent that the invention is capable of both modification and variation from the form shown so that the scope thereof would be limited only by the scope of the claims appended hereto.

I claim:

1. A stud for insertion into the surface of a work piece by its ejection through the bore of an explosively operated stud driving tool, said stud comprising a body having a cylindrical head at its rearward end and having a surface penetrating shank at its forward end terminating in a sharpened point, the junction of said head and said shank providing a shoulder, said stud

also including a tubular frictional retainer carried on said body and having a circular array of radially extending longitudinal flexible fins extending outwardly beyond the largest diameter of the body.

5 2. A stud for insertion into the surface of a work piece by its ejection through the bore of an explosively operated stud driving tool as claimed in claim 1, in which the side walls of a 10 fin are parallel.

15 3. A stud for insertion into the surface of a work piece by its ejection through the bore of an explosively operated stud driving tool as claimed in claim 1, in which each fin is of triangular cross-section.

20 4. A stud for insertion into the surface of a work piece by its ejection through the bore of an explosively operated stud driving tool as claimed in claim 1, in which said frictional retainer comprises a tubular plastic structure of uniform cross-sectional shape throughout its length.

25 5. A stud for insertion into the surface of a work piece by its ejection through the bore of an explosively operated stud driving tool as claimed in claim 1, in which each fin is of spiral configuration.

6. A stud for insertion into the surface of a work piece by its ejection through the bore of an explosively operated stud driving tool as claimed in claim 1, in which the side walls of a fin are parallel; and each fin is of spiral configuration.
